D17-5

EX

OR D 11,743

NO. 11,743

April 20, 1880

(Style 520.)

UNITED STATES PATENT OFFICE.

ALBERT WAGNER, OF NEW YORK, N. Y., ASSIGNOR TO J. ESTEY & CO., OF BRATTLEBOROUGH, VT.

DESIGN FOR AN ORGAN-CASE.

SPECIFICATION forming part of Design No. 11,743, dated April 20, 1880.

Application filed February 3, 1880. Term of patent 14 years.

To all whom it may concern:

Be it known that I, ALBERT WAGNER, of the city, county, and State of New York, have invented or produced a new and original Design for Organ-Cases, (style 520,) which I have assigned to J. Estey & Co., of Brattleborough, Vermont, and of which the following is a specification.

My improved design is clearly shown in 10 the accompanying photographic illustration, in which A indicates the front board of the case; B, the key-board projection above the same; C, the lid covering the key-board; D, the back board of the case, and E E the ends 15 thereof.

The general conformation of the case is similar to that shown in the Patent No. 11,374, granted August 26, 1879, to J. Estey & Co., assignees; but it differs from that and other 20 organ-cases heretofore produced in the particulars hereinafter set forth.

The front board, A, is divided, as usual, into three panels, a a a, which I have ornamented by extending across the center of each a stripe 25 or band, b, of a linear pattern, consisting of a crenelated line in the center, disposed between two sets of straight lines, which are flanked by two rows of dot-like ornaments resembling clover-leaves. The stripes b b may 30 be arranged horizontally or diagonally, as preferred.

The front of the key-board projection B is provided, as usual, with an open-work panel, which I form of one or two elongated openings, with a series of ornaments, c c, which somewhat resemble a Greek cross, arranged 35 therein, as shown.

I form the outer surface of the lid C of longitudinal strips arranged each at a less incline than the general incline of the lid, so that a slight abrupt descent is formed at the front edge of each strip, producing an appearance similar to that of the weather-boarding of a house.

Above the lid is another open-work panel, B', which I form of an elongated opening, within which are arranged a series of disks, d d, and which is divided between the disks by a longitudinal strip, which is crossed by a 45 series of short vertical pieces.

The back board, D, extends upward considerably above the body of the case, its upper portion being unsupported by any bracket, post, or molding at its sides, thus leaving its side edges exposed to view. It is formed of 55 the same width as the body of the case, having straight vertical sides and a substantially straight horizontal top, and upon its front is centrally arranged a music-pocket, F, as in the patent hereinbefore referred to. This 60 pocket I have shaped and decorated as follows: Its front board is formed with wings e e at its upper corners, which each project upwardly and outwardly with one curved and one straight side, and between the wings its 65 upper edge is extended abruptly upward at f. The face of the front board is divided into a series of panels, g g, with arched tops, and concentrically disposed within each arch is a circular design resembling a flower, while the 70 lower portion of the panel is decorated with a linear design suggestive of the stem and leaves of the plant, and with a cross-stripe of lines and dots.

The visible portion of the back board, D, 75 may be divided into a central part, G, above the music-pocket, and two sides, H H, flanking the same. I provide the central portion, G, with a horizontal stripe, h, of carved lines, and above that with scroll-like ornaments i i at each side, and a rosette, j, in the center, and extending centrally above all is a prominent fan-like coronal, I, having preferably a fluted or indented outline, and being embellished with a design in lines some radial from and others 85 concentric with the rosette j.

The side portions, H H, extend higher than heretofore, and are straight across the top. The surface of each is embellished with a design in lines, as shown, consisting of a central 90 rectangular pattern flanked by horizontal stripes and inclosed by a rectangular borderline. Above each side portion, H, extends a crown-rail, k, supported above its top by a series of spindles or balusters, l l, and having 95 preferably an indented upper side.

Each end E of the case is provided with the usual stiles, panel, and key-board bracket, the latter of which I support by a Y-shaped pillar, J, resting on a diagonal bar, m, which 100

(over)

extends from the foot of the case back to the front stile. The front branch of the pillar J terminates in a roll, *n*, the corners of which are preferably scalloped, and a rosette planted upon its outer surface, and below the branches the pillar is first square, and lower down is cylindrical, terminating with a square base upon the bar *m*.

The front surface, *p*, of the key-board bracket 10 and of the end E is ornamented by a series of parallel longitudinal grooves.

Having thus described my improved design, I claim the following as its novel features:

1. The design for an organ-case, consisting 15 of the front board, A, divided into panels *a a*, crossed by ornamental stripes *b b*, substantially as set forth, and shown in the accompanying photograph.

2. The design for an organ-case, consisting 20 of the front of the key-board projection B, provided with an elongated opening or openings, in which a series of ornaments, *c c*, are inserted, substantially as shown in the accompanying photograph.

25 3. The design for the lid of an organ-case, consisting of a series of longitudinal strips arranged at an angle to the general plane and in steps one above another, in similar manner to the weather-boarding of a house, substantially as shown in the accompanying photograph.

30 4. The design for the open-work panel B' above the lid of an organ-case, consisting of an elongated opening with disks *d d* inserted at intervals therein, and with ornamental open-work between the disks, substantially as shown in the accompanying photograph.

35 5. The design for the open-work panel B' of an organ-case, consisting of an elongated opening or openings divided by a longitudinal strip having short transverse branches, substantially as shown in the accompanying photograph.

40 6. The design for the music-pocket F of an organ-case, consisting of the wings *e e*, formed at its upper corners, said wings having each one straight and one curved side, substantially as shown in the accompanying photograph.

45 7. The design for the music-pocket F of an organ-case, consisting of wings *e e*, projecting at its upper corners, and an upward projection, *f*, at its upper edge, substantially as shown in the accompanying photograph.

50 8. The design for the music-pocket F of an organ-case, consisting of circular-topped panels *g g*, which each contain a linear design suggestive of a plant and its flower, substantially as shown in the accompanying photograph.

55 9. The design for an organ-case, consisting 60 of the back board, D, projecting measurably above the body of the case, its projecting portion being of the same width as said body, terminating in a substantially square or horizontal top, and having a music-pocket, F, arranged against its face, substantially as shown 65 in the accompanying photograph.

10. The design for an organ-case, consisting of the back board, D, extending measurably above the body of the case, and surmounted by a fan-like coronal, I, substantially as shown 70 in the accompanying photograph.

11. The design for an organ-case, consisting of the music-pocket F, arranged upon the elevated back board, D, and the exposed rectangular side portions, H H, of said board ornamented with the linear design, substantially 75 as shown in the accompanying photograph.

12. The design for an organ-case, consisting of the elevated back board, D, having a horizontal top, balusters *l l*, and insulated crown-rail *k*, substantially as shown in the accompanying 80 photograph.

13. The design for an organ-case, consisting of the elevated back board, D, extending above the music-pocket F, and ornamented with the 85 horizontal linear stripe *h* and central rosette, *j*, substantially as shown in the accompanying photograph.

14. The design for an organ-case, consisting of the elevated back board, D, formed with 90 the scroll-like ornaments *i i*, and bearing the central rosette, *j*, and fan-like coronal I, substantially as shown in the accompanying photograph.

15. The design for an organ-case, consisting 95 of the elevated back board, D, extending above the music-pocket F, ornamented with the central rosette, *j*, and terminating in the fan-like coronal I, radiating from the said rosette, substantially as shown in the accompanying 100 photograph.

16. The design for the support for the key-board projection of an organ-case, consisting of the Y-shaped pillar J, substantially as shown in the accompanying photograph. 105

17. The design for the support for the key-board projection of an organ-case, consisting of the pillar J, resting on the diagonal bar *m*, substantially as shown in the accompanying photograph. 110

18. The design for the support for the key-board projection of an organ-case, consisting of the Y-shaped pillar J, its front branch terminating in a roll, *n*, substantially as shown in the accompanying photograph. 115

19. The design for the support for the key-board projection of an organ-case, consisting of the pillar J, having a square base, a turned shaft, and a square bifurcated upper portion, its front branch terminating in a roll, *n*, substantially as shown in the accompanying photograph. 120

In witness whereof I have hereunto signed my name in the presence of two subscribing witnesses.

ALBERT WAGNER.
